UNITED STATES PATENT OFFICE.

THOMAS W. BRIGHT, OF ELK, WEST VIRGINIA.

STOVEPIPE-THIMBLE.

No. 825,889.

Specification of Letters Patent.

Patented July 17, 1906.

Application filed August 10, 1905. Serial No. 273,570.

To all whom it may concern:

Be it known that I, THOMAS W. BRIGHT, a citizen of the United States, residing at Elk, in the county of Tucker and State of West Virginia, have invented a new and useful Stovepipe- Thimble, of which the following is a specification.

This invention relates to stovepipe-thimbles.

10 The object of the invention is to provide a thimble adapted to be located at the angle or corner of a chimney instead of on the side, as usual, whereby where the chimney is located in the center of a building and its corners project within each of four rooms on the same floor an efficient connection of each of the rooms may be had with the chimney.

With the above and other objects in view, as will appear as the nature of the invention 20 is better understood, the same consists in the novel construction and combination of parts of a stove-pipe thimble, as will be herein-after fully described and claimed.

In the accompanying drawings, forming a part of this specification, and in which like characters of reference indicate corresponding parts, Figure 1 is a view in horizontal section of a chimney, showing the manner in 25 which the thimble is combined with one corner thereof. Fig. 2 is a perspective detail view of the thimble.

The thimble 1 may be made of any suitable material, such as terra-cotta or cast metal, and is provided at its inner end, or that which 35 will extend into the chimney, with an angular rabbet, the edges 2 of which are at right angles to each other and are adapted to lie flush with the inner walls of the chimney C, as shown in Fig. 1. The outer end of the thimble, or that which will be disposed exteriorly of the chimney, has its sides truncated, forming thereby an angular extension 3, the edges 40 of which are disposed at right angles to each other and parallel with the edges 2 and 45 are adapted to lie flush with the outer walls of the chimney. The extension is provided with a marginal flange 5, the inner edges 6 of which are disposed parallel with the outer

edges 4 of the extension and are adapted to bear squarely against the outer face of the 50 chimney, thereby not only to limit the insertion of the thimble within the thimble-opening, but also operate to form a tight juncture therewith, and thus preclude entrance of moisture to the room in which the thimble is 55 located. As shown in Fig. 2, the exterior surface of the body of the thimble is convex from end to end to cause it to take a firmer hold upon the cement or plaster which is used for securing the thimble in place. The inner 60 surface of the thimble is cylindrical.

By the provision of the rabbet 2 when the thimble is positioned in the chimney there will be no projecting portions on the inner side thereof, which would be objectionable as 65 presenting surfaces upon which soot could lodge, and by the provision of the angular extension the outer end of the thimble is caused to conform to the walls of the chimney, and thereby obviate the presentation of a 70 protuberance that would be unsightly and objectionable. The inner edges 6 of the flange are also of importance, inasmuch as by their provision not only as above pointed out is the admission of moisture to the room prevented, but a neat and finished appearance 75 is given to the article, which greatly enhances its value.

Having thus described the invention, what 80 is claimed is—

A stovepipe-thimble having its inner surface cylindrical and its outer surface convex from end to end, said thimble being provided with an angular rabbet in one end, and at its other end with an angular extension the 85 edges of which are disposed at right angles to each other and parallel with the edges of the rabbet, and a flange extending laterally from the edges of the extension.

In testimony that I claim the foregoing as 90 my own I have hereto affixed my signature in the presence of two witnesses.

THOMAS W. BRIGHT.
